UNITED STATES PATENT OFFICE.

ALBERT J. DREHER, OF CINCINNATI, OHIO, ASSIGNOR TO THE AMERICAN LAUNDRY MACHINERY COMPANY, OF CINCINNATI, OHIO, A CORPORATION OF OHIO.

TIMING DEVICE FOR CENTRIFUGAL MACHINES.

Application filed April 27, 1922. Serial No. 556,899.

This invention relates to improvements in centrifugal extractors, and more particularly, to timing devices therefor.

The objects of this invention are to provide a centrifugal extractor with improved means for automatically stopping operation of the same at a predetermined time; more particularly to provide improved means for automatically cutting out the electric driving motor and at the same time applying a braking action so as to automatically stop the rotation of the basket of the extractor.

It is a further object of this invention to provide improved means for either automatically or manually actuating the means for stopping the operation of the extractor; and also to provide such an automatic stopping device that can be set for any length of operation desired.

20 A further object of the invention is to provide an improved extractor including braking means for the rotatable extractor member, driving or operating means therefor, a latching means for holding the brake relieved and rendering the driving means effective, together with means operable by a single manipulation or a single operator operated member for simultaneously controlling or affecting two or more of the three 25 parts stated, to wit, the brake, the driving means and the latching means.

Further objects of the invention will appear from the following description and claims when considered together with the 35 drawings.

Fig. 1 is a side elevation of a centrifugal extractor embodying my timing device; Fig. 2 is a transverse section of the machine on line 2—2, Fig. 1; Fig. 3 is a section on line 40 3—3, Fig. 2; Fig. 4 is a section on line 4—4, of Figs. 6, 7 and 8; Fig. 5 is a section on line 5—5, of Figs. 6 and 7; Fig. 6 is a section on the line 6—6, of Figs. 4 and 5; Fig. 7 shows in front elevation the dial of 45 the timing mechanism partly broken away; Fig. 8 is a section on the line 8—8, of Figs. 4 and 7; Fig. 9 is a sectional view on the line 9—9 of Fig. 2; Fig. 10 is a section on line 10—10 of Fig. 1; and Fig. 11 is a diagram 50 of the electric circuit.

The casing 1 of the centrifugal extractor encloses a rotatable basket of the usual type which is mounted for rotation upon the spindle 3 provided at its lower end with the pulley 4 for operation by the belt 5, the belt

being driven from the pulley 6 of the electric motor 7. The motor is suitably mounted upon the bracket 8 on the side of the extractor casing and supporting frame.

The brake lever 9 is pivotally mounted at 60 10 upon the base of the machine frame and is provided with the brake shoe 11 which is adapted to engage the pulley 4 upon depression of the treadle end 12 of the lever. The release treadle 13 forms one arm of the bell crank lever which is pivotally mounted at 14 upon the bracket 20 supported upon the base of the machine while the other arm of the bell crank lever is indicated at 15 and is formed with a forked end portion 16 for 70 engagement with a pin 17 on the side of the arm 18. The one end of the arm 18 is fixed to the shaft 19 which is rockably mounted at its two end portions upon the brackets 20 provided on the base portion of the machine. 75 Fixed also upon the shaft 19 is the arm 21, the other end of which is pivotally connected at 22 with the clevis 23. Secured within the lower end of the clevis 23 is the rod or stem 24 which is provided upon its lower end with 80 a ball 25 for engagement in the socket 26 carried by the upper face of the treadle 12. Thus there is provided a positive operative connection between the treadle 13 and the arm 18 as well as the brake lever 9 through 85 the connections just described.

The electric circuit through the motor 7 includes the normally open switch 27 provided within the casing 28 upon the inner wall of which there is also provided the guide 90 block 29. The casing 28 is suitably mounted upon the under part of the casing 1 as indicated in the drawing. The switch 27 is controlled by means of the stem 30 which extends through the swivel block 31 and has 95 a shoulder 32 for engagement therewith. The swivel block 31 is mounted in the arm 18 and upon elevation of the arm so as to cause the swivel block 31 to engage the shoulder 32, the stem 30 will be raised so as to close 100 the switch 27.

The other end of the arm 18 is pivotally connected with the link 33, the other end of this link being pivoted to the clevis 34 provided upon the lower end of the latch 105 stem 35 which extends upwardly through the bracket arms 36 and 37. Suitably mounted upon the bracket 38 on the wall of the casing 1 I have provided the casing 39 which encloses the timing mechanism which 110

constitutes the main feature of my present invention. The shaft 40 is suitably mounted for rotation within the casing 39 and has loosely mounted upon its outer end portion 5 the hub 41 upon which there is fixed the dial 42. The shaft 40 has a collar 43 which constitutes an abutment for one end of the spring 44 while the other end thereof abuts against the bottom of a cut-out portion in 10 the hub 41, as clearly shown in Fig. 4; so that the hub 41 with the dial 42 can be pulled outwardly against the tension of the spring 44 for the purpose of setting the same as will later appear.

15 The inner end portion of the hub 41 is provided with the clutch face 45 for engagement with the companion clutch member 46 fixedly mounted upon the shaft 40. The shaft 40 is driven from the motor 7 through the drive 20 connection 47 between the rotor of the motor and the flexible shaft 48 which in turn drives the shaft 49. The worm 50 fixed upon the shaft 49 in turn drives the gear 51 which is fixed upon the shaft 52 suitably mounted in 25 the casing 39. The shaft 52 has fixedly mounted thereupon the pinion 53 meshing with the gear 54 fixed upon the shaft 55 which shaft has fixed thereon the worm 56 meshing with the gear 57. Gear 57 being 30 fixedly mounted upon the shaft 40 provides driving connection for the dial 42 when the clutch members 45 and 46 are normally held in engagement by the spring 44.

35 The latch stem 35 is provided with the shoulder 58 for supporting engagement by the tooth 59 of the latch member 60 which extends through the casing 39. The spring 61 normally forces the latch 60 toward engagement with the latch stem 35 but may be 40 withdrawn from such engagement by operation of the lever arm 62 pivoted in the casing and provided at its one end with the fork 63 for engagement with the pin 64 provided in the latch 60. The lever or trip arm 62 45 extends outwardly through an enlarged opening in the casing 39 so as to extend in the path of the trip member 65 provided upon the dial 42. Thus it will be seen that upon pulling out the hub 41 and turning the 50 dial 42 to the left or in counter-clockwise direction, as viewed in Fig. 7, the device can be set for any desired length of operation by bringing any number marked upon the face of the dial, corresponding to the number of 55 minutes of operation desired, to a point opposite the index 66 provided upon the casing 39. Such movement of the dial in a counter-clockwise direction will move the trip 65 away from the lever 62, but upon operation 60 of the machine and the rotation of the dial 42 in a clockwise direction through the train of gears above described, the trip 65 will at the termination of the period for which 65 the device is set arrive at the position indicated in Fig. 7 so as to trip the lever 62 and

withdraw the latch 60 against the tension of the spring 61. In this way there is effected the release of the latch stem 35 with the simultaneous lowering of the arm 18 so as to permit stem 30 to lower and open the 70 switch 27 and the brake 11 is applied through the connections already described.

75 Thus when it is desired to operate the machine, the timing mechanism will be set for the period of operation desired, the latch stem 35 will be raised by depression of treadle 13 and held in such position by engagement of the latch 60, the switch 27 being closed and the brake being released by the same manipulation. Should it be desired 80 during the operation of the machine and before expiration of the time for which the device is set, to stop the machine, this may be done by the operator himself tripping the lever 62 so as to release the latch 60 to permit breaking of the circuit through the motor as well as the application of the brake in the manner above described. Should, however, the machine be permitted to run 85 throughout the entire period for which the timing device is set, the trip 65 will eventually engage the lever 62 so as to automatically release the latch stem, cut out the motor and stop rotation of the basket.

90 What I claim is:

1. A centrifugal extractor, comprising a 95 rotatable extracting member, operating means therefor, a controller therefor, braking means for said member, latching means for said controller and braking means, timing mechanism controlling said latching means, and means operated by a single manipulation for actuating said controller for starting the operating means and to also relieve said brake and cause the latching 100 means to latch both the controller and brake.

105 2. A centrifugal extractor, comprising a rotatable extracting member, operating means therefor, a controller therefor, braking means for said member, latching means for said controller and braking means, timing mechanism controlling said latching means, and a single operator operated member arranged to actuate said controller for 110 starting the operating means and to also relieve said brake and cause the latching means to latch both the controller and brake.

115 3. A centrifugal extractor, comprising a rotatable extracting member, an electric motor for rotating the same, a controlling 120 switch therefor, braking means for said member, latching means for said switch and braking means, timing mechanism controlling said latching means, and means operable by a single manipulation for actuating 125 said switch for starting the operating means and to also relieve said brake and cause the latching means to latch both the switch and brake.

130 4. A centrifugal extractor, comprising a

- rotatable extracting member, an electric motor for rotating the same, a controlling switch therefor, braking means for said member, latching means for said switch and 5 braking means, timing mechanism controlling said latching means, and a single operator operated member arranged to actuate said switch for starting the operating means and to also relieve said brake and cause the 10 latching means to latch both the switch and brake.
5. A centrifugal extractor, comprising a rotatable basket, driving means therefor, braking means therefor, latching means, and 15 timing mechanism controlling said latching means, in combination with means for actuating said braking means adapted by its operation to also control said driving means.
6. A centrifugal extractor, comprising a 20 rotatable basket, driving means therefor, braking means therefor, latching means, and timing mechanism controlling said latching means, in combination with means for actuating said braking means adapted by its 25 operation to also control said driving means and actuate said latching means.
7. A centrifugal extractor, comprising a rotatable basket, driving means therefor, braking means therefor, latching means, and 30 timing mechanism controlling said latching means, in combination with means for controlling said driving means adapted by its operation to also relieve said braking means.
8. A centrifugal extractor, comprising a 35 rotatable basket, driving means therefor, braking means therefor, latching means, and timing mechanism controlling said latching means, in combination with means for controlling said driving means adapted by its 40 operation to also set said latching means.
9. A centrifugal extractor, comprising a rotatable basket, driving means therefor, braking means therefor, latching means, and timing mechanism controlling said latching means, in combination with means for actuating said driving means adapted by its 45 operation to also relieve said braking means and set said latching means.
10. A centrifugal extractor, comprising a rotatable basket, driving means therefor, braking means therefor, latching means, and timing mechanism controlling said latching means, in combination with means for setting said latching means adapted by its 50 operation to also render said driving means 55 effective.
11. A centrifugal extractor, comprising a rotatable basket, driving means therefor, braking means therefor, latching means, and timing mechanism controlling said latching means, in combination with means for setting said latching means adapted by its 60 operation to also relieve said braking means and render said latching means effective.
- In testimony whereof I hereby affix my 65 signature.

ALBERT J. DREHER.
